Primary Examiner — Susan Bennett Hattan*Assistant Examiner* — Brett Miller(74) *Attorney, Agent, or Firm* — Sterne, Kessler, Goldstein & Fox P.L.L.C.(57) **CLAIM**

The ornamental design for a building, as shown and described.

DESCRIPTION

FIG. 1 is a top, front, right perspective view of a building showing our new design.

FIG. 2 is a front view thereof;

FIG. 3 is a rear view thereof;

FIG. 4 is a left side view thereof;

FIG. 5 is a right side view thereof; and,

FIG. 6 is a top view thereof.

The shade lines in the figures show contour and not surface ornamentation.

The oblique shade lines in the figures show transparency or translucency.

Portions of the building not shown in the figures form no part of the claimed design.

1 Claim, 4 Drawing Sheets(56)
